UNITED STATES PATENT OFFICE.

ALBERT E. SIDNELL, OF SALT LAKE CITY, UTAH, ASSIGNOR TO THE UTAH RADIO PRODUCTS COMPANY, OF SALT LAKE CITY, UTAH, A CORPORATION OF UTAH.

DESIGN FOR A LOUD SPEAKER.

Application filed July 18, 1925. Serial No. 14,140. Term of patent 7 years.

To all whom it may concern:

Be it known that I, ALBERT E. SIDNELL, a citizen of the United States, residing in Salt Lake City, county of Salt Lake, and State of Utah, have invented a new, original, and ornamental Design for a Loud Speaker, of which the following is a specification, reference being had to the accompanying drawing, forming part thereof.

The figure represents a perspective view of a loud speaker showing my new design.

The cross-lined panels in the figure do not indicate any color, but denote a textile fabric.

I claim:

The ornamental design for a loud speaker, as shown and described.

ALBERT E. SIDNELL.
